CLAIM

The ornamental design for a sandal, as shown and described.

DESCRIPTION

FIG. 1 is a top perspective view of a sandal showing my new design;

FIG. 2 is a bottom perspective view thereof;

FIG. 3 is a top view thereof;

FIG. 4 is a side view thereof;

FIG. 5 is an opposing side view thereof, of that shown in FIG. 4;

FIG. 6 is a front view thereof; and,

FIG. 7 is a rear view thereof.

The broken lines shown in FIGS. 1-7 are shown for environmental purposes only and form no part of the claimed design.
